W. H. RICHMAN

PROCESS OF MAKING METALLIC CANS AND ARTICLES PRODUCED

Filed Oct. 4, 1921

FIG. I.

FIG. V.

FIG. VI.

FIG. III.

FIG. II.

FIG. IV.

Inventor:

WALTER H. RICHMAN,
By *Walter E. Page*,
Attorney

UNITED STATES PATENT OFFICE.

WALTER H. RICHMAN, OF PHILADELPHIA, PENNSYLVANIA.

PROCESS OF MAKING METALLIC CANS AND ARTICLES PRODUCED.

Original application filed November 20, 1919, Serial No. 329,446. Divided and this application filed October 4, 1921. Serial No. 505,345.

To all whom it may concern:

Be it known that I, WALTER H. RICHMAN, a citizen of the United States, and resident of Philadelphia, Pennsylvania, have invented certain new and useful Improvements in Processes of Making Metallic Cans and Articles Produced, of which the following is a specification.

My invention relates to the method of 10 and means for producing containers of the type disclosed in Letters Patent of the United States 1,395,298 granted to me November 1, 1921 pursuant to application Serial 329,446 filed November 20, 1919, of 15 which this is a division.

My invention relates to sheet metal cans adapted for the transportation and storage of dairy products and particularly ice cream. Such cans are used by wholesalers to deliver 20 such products to retailers, and are used by the latter to hold such products while they are being dispensed; the emptied cans being thereafter returned to the wholesalers to be refilled and again distributed. Consequently, such cans must be extremely durable 25 to withstand the rough handling and stresses and wear to which they are inevitably subjected. Moreover, as such containers are retained in salt ice water to preserve their 30 contents, their bodies must be permanently liquid tight and, to prevent contamination of their contents, they must be adapted to be hermetically sealed by closures which can be instantly opened and shut and which may 35 be opened to the full diameter of the cans, to facilitate dispensation of their contents. Furthermore, such containers should not have any crevices or joints which cannot be 40 readily cleaned of every vestige of such products, by mechanical means, for such products readily and rapidly decompose.

Therefore, the object and effect of my invention is to produce cans having the characteristics above contemplated. Before my invention, it was customary to make ice cream cans of primarily flat tinned sheets of iron or steel, such as is used for roofing. At first, such cans were merely soldered at their joints to hold the parts together. However, 45 such cans were found to be so weak and lacking in durability that they were superseded by cans likewise formed of such previously tinned sheets but with the edges of

the sheets lapped and riveted before they were soldered and with the crevices thus 55 formed filled with solder. However, as the wear and salt water to which such cans are subjected as aforesaid, cause them to rapidly corrode and rust; endeavors were made to retin them. However, in order to properly 60 tin or retin any article, it must be submerged in a molten bath of tin which is practically chemically pure. However, upon any attempt to submerge a soldered can in a pure 65 tin bath, the solder, which is substantially half lead, is melted off and pollutes such tin bath, so as to render the latter unfit for subsequent use. Therefore, attempts were made to prepare soldered cans for retinning by melting the solder from them before submerging them in the tin bath. However, 70 such procedure not only rendered the cost of retinning prohibitive but it was found to be practically impossible to thus entirely eliminate the solder; so that the initially pure tin 75 bath was polluted by the soldered cans even after such preliminary treatment.

Therefore, the purpose and effect of my invention is to produce a solderless ice cream can having the other characteristics above 80 described.

My invention includes the various novel features of procedure and product herein-after more definitely specified.

In the drawings; Fig. I is a vertical diametrical sectional view of an ice cream can produced in accordance with my invention; a portion of the can body being broken away.

Fig. II is a fragmentary diametrical sectional view, showing the blank for the can bottom closure indicated in Fig. I; in the form in which it is produced by pressing a primarily plane sheet with dies.

Fig. III is a fragmentary diametrical sectional view of such a bottom closure blank with a roller adapted to press and swage its upper annular corner to deform the latter.

Fig. IV shows the structure of Fig. I deformed by pressing and swaging its upper 100 annular corner to an acute angle and substantially sharp edge, by said means shown in Fig. III.

Fig. V is a fragmentary radial sectional view of the can body with said bottom closure forced therein to a tight fit, and a

roller adapted to spin the marginal flange of said closure over the outside of said body to the form shown in Fig. I.

Fig. VI shows the completion of the bottom closure flange spinning operation.

In said figures; the body of the can 1 is made of a sheet of metal with the edges brought together and butt welded, forming a flush longitudinal seam 2. That is to say; 10 the metal of said body 1 at said seam is substantially smooth both inside and outside of the can, so as to cooperate with the bottom closure to make a joint without a crevice by the several steps hereinafter described. It 15 may be observed that it would be impossible to make such a joint by the method herein contemplated if said body 1 were not thus produced in substantially circular seamless form.

20 In order to facilitate driving the bottom closure 3 into said body 1; I prefer to slightly flare the bottom edge of said body, as indicated at 4 in Fig. V. The bottom closure 3 of said body 1 is formed by successive operations upon a suitable blank, which is a circular disk of primarily plane sheet metal. Said blank is pressed by suitable dies 6 to the form shown in Fig. II, wherein its upturned annular corner 7 is 25 rounded outwardly into the cylindrical side wall 8 of said closure, the outside diameter of which is so proportioned as to be driven into said body 1, to the extent limited by the transversely extending plane flange 10 at the 30 bottom of said closure wall 8. However, such a rounded corner would, of course, afford a crevice in which the lacteal products aforesaid would lodge so that they could not be removed by the ordinary cleaning operation. Therefore, I proceed to deform said 35 annular corner 7 by pressing and swaging the same to an acute angle with respect to the wall 8 and substantially sharp edge, conveniently by the means shown in Fig. III, to wit, a spinning roller 11 which is caused to traverse said corner while said wall 8 is supported within the encircling die member 6. The effect of that operation is to 40 change the configuration of said closure from that shown in Fig. II to that shown in Fig. IV, wherein the upper annular edge 12 of said bottom closure 3 is substantially sharp and circular.

45 Said bottom closure 3, in the form shown in Fig. IV, is then forcibly thrust into said body 1, to the position shown in Fig. V. In that operation, said substantially sharp edge 12 scrapes the interior wall of said body 1 into a close fit therein and slightly expands 50 said body as indicated in Fig. V.

55 Thereupon, I prefer to subject said body 1 to pressing action on its exterior substantially opposite the point where said edge 12 lies so that said body will be trued up and forced in against the upstanding side wall

8 of said closure 5 and against said edge 12. Such pressure may be conveniently applied by the spinning roller 14 which, as indicated in Fig. VI, may also be used to upturn said primarily transversely extending bottom 70 closure flange 10 to the cylindrical form shown in Figs. I and VI. Although said flange may be pressed against the side of the body 1 tightly enough to be retained thereon; I prefer to then spot weld said flange to 75 said body.

Moreover, said upturned edge 12 may be treated locally by a tool inserted into the can after said bottom closure is pressed in position, said tool being adapted to spin, 80 roll, stamp or press said edge 12 over to insure close contact with the wall of said body 1. Such spinning or other action may, at the same time, grind said edge 12 to facilitate its slight deformation to close fit. 85

However, the effect of the operations above contemplated is to form a joint between said can body 1 and its bottom closure 5 such that the subsequent tinning operation will cover it and present a smooth 90 surface on which none of the contents will lodge in such manner as to remain after the can is subjected to the ordinary cleaning process. Moreover, no solder is necessary at any point and hence when the primary coat 95 of tin has worn off, my improved can is susceptible of being retinned without any preliminary operation of removing solder.

Although I have illustrated my invention with reference to an ice cream can which is of substantially uniform cylindrical configuration from the bottom to the open top thereof; it is to be understood that my invention may be applied to containers of other forms. Therefore, I do not desire to 100 limit myself to the precise details of construction, arrangement or procedure herein set forth, as it is obvious that various modifications may be made therein, without departing from the essential features of my invention, as defined in the appended claims. 105

I claim:

1. The method of making a solderless ice cream can, which includes forming a cylindrical tubular can body by bending and 110 butt welding opposite edges of a primarily flat sheet of metal; outwardly flaring the bottom end of said body; forming a bottom closure for said body by die pressing a primarily flat circular disk of metal to offset 115 the central portion thereof, to render said central portion of concavo-convex form with a cylindrical wall connected therewith by a rounded corner and merging into a plane marginal flange; deforming said bottom closure corner by pressing and swaging the same to an acute angle with respect to said wall and substantially sharp edge; forcing the offset portion of said bottom closure 120 into said lower end of said body to the ex- 125

tent of the wall on said closure; thereby drive fitting said sharpened closure edge against the inner wall of said body; pressing said body inwardly opposite to said closure edge and wall; upturning the flange on said closure against the cylindrical lower edge of said body and pressing it inwardly into contact with said body; spot welding said closure flange to said body; thereafter 10 contemporaneously coating the outer and inner surfaces of said can by immersing it in a molten tin bath.

2. The method of providing a cylindrical tubular container body with a permanent closure, which includes outwardly flaring the end of said body; forming a closure with a concave central portion extending to a substantially sharp circular edge in unitary relation with a cylindrical wall and flange 20 extending transversely to said wall; drive fitting said closure into the flared end of said body; pressing said body inwardly at the region of said closure edge; and upturning said closure flange into contact with the outer cylindrical surface of said body.

3. The method of providing a cylindrical tubular container body with a permanent closure, which includes outwardly flaring the end of said body; forming a closure with a concave central portion extending to a substantially sharp circular edge in unitary relation with a cylindrical wall; drive fitting said closure into the flared end of said body; pressing said body inwardly at the region of said closure edge; and welding 35 said body to said closure.

4. The method of providing a cylindrical tubular container body with a permanent closure, which includes forming a closure with a concave central portion extending to a sharp acute angular edge; tightly fitting said closure in said body with its outer surface spaced inwardly from the end of said body; welding said body to said closure; and coating said body and closure inside and outside by immersing the structure in a molten metal bath.

In testimony whereof, I affix my signature.

WALTER H. RICHMAN.
